(57) **CLAIM**

The ornamental design for a remote control device, as shown and described.

DESCRIPTION

FIG. 1 is an isometric view of a remote control device according to an embodiment of the invention, the remote control device being shown in an open orientation;

FIG. 2 is a left-side view thereof;

FIG. 3 is a top view thereof;

FIG. 4 is a right-side view thereof;

FIG. 5 is a bottom view thereof;

FIG. 6 is a front view thereof;

FIG. 7 is a rear view thereof; and,

FIG. 8 is an isometric view of the remote control device of FIG. 1, but showing the remote control device in a closed orientation.
